(57) **CLAIM**

The ornamental design for a wand with double nozzle and soap reservoir, as shown and described.

DESCRIPTION

FIG. 1 is a first perspective representational view of the wand with double nozzle and soap reservoir;

FIG. 2 is a second perspective representational view of the wand with double nozzle and soap reservoir;

FIG. 3 is a first side view of the wand with double nozzle and soap reservoir;

FIG. 4 is a top view of the wand with double nozzle and soap reservoir;

FIG. 5 is a second side view of the wand with double nozzle and soap reservoir;

FIG. 6 is a bottom view of the wand with double nozzle and soap reservoir;

FIG. 7 is a first end view of the wand with double nozzle and soap reservoir; and,

FIG. 8 is a second end view of the wand with double nozzle and soap reservoir.
